UNITED STATES PATENT OFFICE.

ROBERT W. HARDIE, OF WHITE PLAINS, NEW YORK.

MEANS FOR CONDITIONING VAPOR.

1,388,143.

Specification of Letters Patent. Patented Aug. 16, 1921.

Application filed August 20, 1920. Serial No. 404,951.

To all whom it may concern:

Be it known that I, ROBERT W. HARDIE, a citizen of the United States, residing at White Plains, in the county of Westchester, 5 in the State of New York, have invented new and useful Means for Conditioning Vapor, of which the following is a specification.

This invention relates to means for conditioning and introducing vapor into an indoor atmosphere to increase the relative humidity thereof.

The vapor received by this device may be in the nature of what is generally known as 15 steam, or it may be what is commonly referred to as vapor, as distinguished from steam, that is vapor arising from water, heated to a lower temperature than 212° F. at atmospheric pressure. The term vapor is 20 used herein to include both steam and vapor.

In order to humidify an indoor atmosphere, that is to raise the relative humidity thereof by means of vapor diffused into the atmosphere, it is necessary that the particles 25 of water in the vapor shall be sufficiently fine to be readily absorbed by the drying power of the air, otherwise the vapor will condense at or near the point of delivery of the vapor into the atmosphere, and will not 30 be taken up by the atmosphere and become diffused therein in accordance with what is known as the law of diffusion of gases.

Efforts have heretofore been made to increase the relative humidity of an indoor 35 atmosphere by means of a casing, or water back placed within the furnace of a heat generator, and connected at one end with a water supply, and at the other end with a pipe that discharged from its free outer end 40 into a room or fresh air intake, the vapor generated in the casing or water back.

But such efforts have been unsuccessful, for the reason that the vapor entered the interior of a building under positive impulsive 45 effect, heavily laden with moisture, making the vapor visible to an objectionable extent, and because of the fact that the moisture from the overladen vapor cannot in such condition be absorbed by the indoor 50 air, it condensed, and became deposited on the walls, woodwork and surrounding objects near to the point of delivery into the indoor atmosphere.

Other efforts have been made to overcome 55 the injurious effects of projecting into an indoor atmosphere raw steam or vapor

heavily charged with moisture, by providing a discharge pipe with an apertured head or terminal covered or otherwise provided with layers of absorbent material such as 60 cloth.

Those efforts have likewise proved impracticable for the reason that such material has no well defined apertures or orifices for vapor to pass through, and consequently the 65 vapor condensed on the absorbent material, instead of passing therethrough, and saturated said material with the water of condensation.

A secondary vaporization from the outer 70 surface of the absorbent material takes place under such conditions without any of the original vapor passing through said material, but the revaporization produces no practical humidifying effect whatever. 75

Such efforts moreover, when designed for humidifying an indoor atmosphere, proved impractical for the further reason that absorbent material saturated with water at a high temperature, and exposed to the atmosphere forms a positive incubating bed 80 for injurious bacteria.

This invention has for one of its main objects to provide means for reducing vapor of varying densities and of varying expansive impulses into substantially atmospheric pressure and thereby enable the vapor when discharged into the atmosphere to be readily absorbed by, and diffused therein. 85

Another object of the invention is to provide means for preventing the vapor from condensing while being discharged into the atmosphere, and for raising the temperature of the atmosphere at the point of delivery of the vapor therein so as to increase the capacity of the air at that point for receiving vapor. 90

With the foregoing, and other objects in view, hereinafter stated, the invention consists of the novel construction, combination, 100 and arrangement of parts hereinafter more specifically stated, and illustrated in the accompanying drawings, wherein is shown a device embodying the structure of the invention in its preferred form, but it is to be understood that changes, variations and modifications may be resorted to without departing from the scope of the invention. 105

In describing the invention in detail reference is had to the accompanying drawings which form a part of this specification, and wherein like characters of refer- 110

ence indicate corresponding parts throughout the several views and wherein Figure 1, is a side elevation partly in section of a device embodying the invention, and Fig. 2 is a plan of the top of a pressure reducing member shown in Fig. 1.

In carrying out the invention a vapor generator is provided of any suitable construction, capable of converting water into vapor.

In the construction shown in the drawings a heat generator 1, is provided with a coil, receptacle, or water back 2, placed within the furnace of the generator.

15 One end of the water back is connected with a pipe 3, extending upward from the water back, and communicating with the interior of a water supply tank 4. The tank is supplied with water by means of a supply pipe 5 leading to a water main, and provided with a float operated valve 6.

The tank may however be supplied with water in any other suitable manner if desired.

25 The other end of the water back is connected by means of an upwardly extending pipe 7, with the inlet aperture of an open topped vapor receiving receptacle or casing 9, forming a vapor expansion and heat radiating member.

The heat generator, with its coil, receptacle or water back, and the water tank connected with the water back and provided with an automatic float valve are all of old 35 and well known construction, and form no part of the invention. Any other form of vapor generator may moreover be used instead of the one shown herein if desired.

As the water delivered from the supply 40 tank 4, into the water back 2, becomes converted into vapor, the vapor passes outward from the water back through the pipe 7, into the receptacle or casing 9. If the open top of the receptacle be unobstructed, the vapor 45 would pass into the atmosphere in a raw condition, and in such volume that it could not be absorbed by the air, and consequently would become condensed at or near the point of discharge into the atmosphere.

50 To prevent a precipitous discharge of an undesirable amount of vapor into the atmosphere under pressure or impulsive effect, this invention provides a pressure reducing member, which closes the discharge opening 55 of said casing against a too free discharge of vapor, at the same time permitting the desired amount of vapor to pass through said member.

In cases where a water back is used with 60 in the furnace of a heat generator to produce vapor, and a fire is started quickly in the furnace, steam may be generated so rapidly that the pressure reducing member will cause a back pressure on the steam or vapor 65 within the receptacle or casing 9. There-

fore, when the vapor generator used includes a water back in the furnace, it is desirable to make the radiating area of the wall of the receptacle or casing 9, of sufficient size to counter-balance by its radiating 70 effect, the area of the heating surface of the water back.

Where this invention is employed without using a water back in a furnace the area of the receptacle or casing need not be 75 increased for such purpose, and the casing need not be used for either an expansion or a radiating member.

The pressure reducing member in its preferred form comprises a plurality of layers 80 8, of closely woven wire strands which may be bound together at their outer margins in any suitable manner, such as by means of a band having margins 14 overlapping the outer margins of the layers of wire strands. 85

In the drawings the layers of wire strands are shown spaced apart, for convenience of illustration, but in use the layers are laid close together.

The superposed layers of wire strands 90 produce a multiplicity of fine restricted apertures, that exert a retarding frictional effect on the vapor passing through said member, and reduce the initial expansive and impulsive effect of the vapor, to atmospheric conditions, thereby permitting the vapor to pass readily into the atmosphere, and become absorbed thereby. 95

In humidifying the indoor atmosphere 100 of a building by adding vapor to the atmosphere, the greatest difficulty is found in transferring the vapor into the atmosphere in such a manner that the vapor will not condense before being taken up, and absorbed by the atmosphere. 105

In this connection the pressure reducing member performs an important function, in addition to its pressure reducing qualities. The superposed layers of wire strands make a body that absorbs heat from 110 the vapor passing through the pressure reducing member, and from the vapor back of said member, and that heat is radiated by said member outwardly into the atmosphere, opposite to said member, thereby increasing the temperature of the air receiving the vapor discharged through the pressure reducing member, and consequently increasing its capacity for receiving vapor, and in that way preventing the vapor from 115 condensing near its point of discharge from the casing. 120

The pressure reducing member may be connected with, or secured to, the vapor receiving casing in any desired manner. 125

The device in the form illustrated and described herein is well adapted to be used in connection with the fresh air intake of a building, and that may be done by inclosing the receptacle 9, with its pressure reducing 130

member, within an intake casing 10, open at one end to the outer atmosphere, and connected with a discharge flue 11, formed in a wall or partition 12, of a building, and 5 provided with a register 13, of any ordinary construction.

In the construction shown the receptacle or casing 9 is provided with an open top for the discharge of vapor therefrom, instead of 10 from the side of the casing or receptacle. That is not an essential feature of the invention however, and may be modified if desired.

What I claim as new and desire to secure 15 by Letters Patent is:

1. In an air humidifying device, the combination of a vapor generator, a vapor expansion casing connected therewith and provided with a discharge opening, and a pressure 20 reducing and heat radiating member covering said opening and comprising a plurality of superposed layers of woven wire strands, limiting the discharge of vapor from said casing, and radiating heat into the 25 atmosphere adjacent to said opening.

2. In an air humidifying device, the combination of a vapor generator, a vapor expansion casing connected therewith and provided with a discharge opening, and a pressure 25

reducing and heat radiating member 30 covering said opening and comprising a plurality of superposed layers of woven wire strands, secured together independently of said casing, said member limiting the discharge of vapor from said casing and radiating heat into the atmosphere adjacent to said opening.

3. In an air humidifying device, the combination of a vapor generator, a vapor expansion casing connected therewith and provided with a vapor discharge opening, and a pressure reducing and heat radiating member 40 covering said opening and comprising a body of interwoven wire strands limiting the passage of vapor from said casing, and radiating heat into the atmosphere adjacent to said discharge opening.

4. In an air humidifying device, the combination of a vapor generator, an open topped vapor expansion receptacle connected with said generator, and a vapor restraining and heat radiating member covering said open top and comprising a plurality of superposed layers of woven wire strands.

ROBERT W. HARDIE.
